UNITED STATES PATENT OFFICE.

PHILIP H. CHASE, OF EAST ORANGE, NEW JERSEY.

ELECTRIC SWITCH.

1,387,686.

Specification of Letters Patent. Patented Aug. 16, 1921.

Original application filed February 28, 1916, Serial No. 80,923. Divided and this application filed November 4, 1916. Serial No. 129,610.

To all whom it may concern:

Be it known that I, PHILIP H. CHASE, a citizen of the United States, and a resident of East Orange, in the county of Essex and 5 State of New Jersey, have invented an Improvement in Electric Switches, of which the following is a specification.

This invention relates to electric switches, and with regard to certain more specific features, to safety devices for use in connection with manually-operated disconnecting switches for high-voltage circuits. The present application is a division of my application, Serial No. 80,923, filed February 28, 15 1916.

Among the objects of the present invention may be noted the provision of a practical and effective switch in which the operator cannot remove the operating hook 20 from the switch blade at certain times during the cycle of operation of the switch; the provision of a simple and inexpensive safety device to prevent improper manipulation of a high-voltage switch in the hands of an inefficient or careless operator; the provision of improved apparatus of the above type, of reliable action and durable under conditions of use; and the provision of a switch in which the protective features are effective 25 automatically and the danger of improper handling is reduced to a minimum. Other objects will be in part obvious and in part pointed out hereinafter.

The invention accordingly comprises the 30 features of construction, combinations of elements and arrangements of parts which are to be exemplified in the structure hereinafter described, and the scope of the application of which will be indicated in the following claims.

In the accompanying drawings, in which is shown one of the many possible embodiments of this invention,

Figure 1 is a top plan view of a switch 45 in which the blade handle is extended outwardly (away from the blade pivot), and is apertured to receive the shield, a lock or safety catch being provided to hold the switch in its closed position.

Fig. 2 is a side elevation of Fig. 1.

Fig. 3 is an end elevation, partly in section, of Fig. 2.

Fig. 4 is similar to Fig. 2, except that the switch blade is shown partly open and certain parts are illustrated in section to show 55 more clearly the internal structure.

Fig. 5 illustrates a preferred form of hook.

Similar reference characters indicate similar parts throughout the several views of 60 the drawings.

In considering the relation of this invention to the prior art, it may be noted that for some time past the users of manually operated switches, especially on high-voltage 65 circuits, have encountered trouble through the failure of the operators to close the switches completely, or to open them far enough to break any arc that might form. These switches usually comprise simply, a 70 pair of spaced and relatively insulated contact-blocks on which are mounted respectively a pivoted switch-blade and a pair of jaw-clips with which the blade contacts when the switch is closed. The blade may be in 75 one or more parts, according to the size of the switch and the preference of the designer. In a double-throw switch, there is an additional contact-block, insulated relatively to the other two, and provided with 80 a pair of jaw-clips to receive the switch blade when the switch is in the second of its two circuit-closing positions. There are a number of varieties of these switches such as double- and triple-pole switches, but it 85 will suffice for the purpose of the present description to confine the illustrations to a single-pole single-throw switch, it being understood that many if not all of the advantageous features of the present invention are 90 applicable to double-throw, and multiple-pole, and other modifications of the prior-art switching devices.

Referring now more particularly to the accompanying drawings, there is illustrated 95 at 1 a base or contact-block upon which are mounted the usual jaw-clips 2 adapted to receive the blade 3, which is pivotally supported upon another contact-block (not shown). The blade 3 is shown as divided 100 in two parts, and there are therefore two pairs of the jaw-clips 2 coöoperating therewith when the blade is in its circuit-closing position illustrated more clearly in Fig. 2.

When the switch is to be opened, the operator inserts in the aperture 7 in the blade 3 the nose 9 of a hook 10 preferably of the general type illustrated in Fig. 5. The nose 5 passes readily through the large part 11 of the aperture 7, but is too large to pass through the smaller parts 12, 13, of said aperture.

The fixed shield or guide 16 coöperates 10 with the aperture 7 indirectly by guiding a pivoted latch or lock 25 to cause the annular extension 26 thereof to shield or blanket the aperture 7 whenever the catch 28 of the lock 25 abuts against the outer surface 29 15 of the fixed shield 16. When the switch blade 3 is in its closed position, shown in Fig. 2, the catch 28 hooks under the shoulder 31 on the fixed shield 16, and the blade 3 is thus held closed against accidental displacement. The blade or leaf-springs 32, 33, tend 20 to press the lock 25 clockwise into locking position.

The operator, in order to pull the blade 3 away from the jaw-clips 2 to open the switch, inserts the nose 9 of the hook 10 into the aperture 7 until the shank 14 of said hook is in said aperture. The operator then pulls in an upward direction on the hook. This causes the hook to enter the upper reduced portion 12 of the aperture 7, thereby 30 rotating the lock 25 counter-clockwise and against the action of the springs 32, 33, and as a result the catch 28 shifts toward the right to a position beyond the outer end of 35 the shoulder 31. This unlocks the switch and permits the operator to pull the switch blade upward (counter-clockwise) until the switch is entirely open. Then when he releases the pull on the hook, the leaf-springs 40 32, 33, cause the lock 25 to return clockwise to its position of rest, with the annular portion 26 thereof against the stop surface 35 of the blade 3. The aperture 7 is then the same size as it is in Fig. 2, and the operator 45 can readily remove the hook 10 therefrom.

If, however, the operator attempts to remove the hook from the switch blade while the left surface 36 of the catch 28 on the lock 25 engages the outer surface 29 of the 50 fixed shield 16, he will be unable to do so, because the annular extension 26 of the lock 25 will be displaced counter-clockwise about the pivot 27 of said lock, as in Fig. 4, and this counter-clockwise displacement of the 55 lock 25 causes said annular portion 26 thereof to shield or blanket the aperture 7 to such an extent that no part of the aperture is large enough to permit the nose 9 of the hook 10 to pass through it. The operator 60 is thus unable to remove the hook from the switch blade throughout a predetermined range or portion of the movement of the blade. By suitably proportioning the parts, it is impossible for the operator, either 65 through accident or carelessness, to remove

the hook before he has completely opened the switch by pulling the blade 3 upward until it is entirely out of contact with the jaw-clips 2.

The vertical length of the outer surface 70 29 of the shield 16 determines the range of movement of blade 3 through which the operator is prevented from removing the hook 10: the parts may be so designed as to have 75 this range of movement such that the operator must pull the blade out of contact with the jaw-clips, and then through a further angle in order to make sure that any arcing at the contacts is broken prior to disconnection; or the protected range may extend 80 only to the point where contact is actually broken; or the shield 16 may be made shorter, with a corresponding reduction of cost, and the protected range of movement 85 will then extend from the closed position of the switch throughout only part of the angle through which the blade is in contact with the jaw-clips 2.

In closing the switch, a similar protection is afforded, in that the operator cannot 90 remove the hook until the switch is substantially or entirely closed and locked. As the switch blade moves downwardly into circuit-closing position, the catch 28 rides outwardly on the beveled surface 38 of the 95 shield 16, thereby swinging the lock 25 counter-clockwise against the action of springs 32, 33. During the ensuing downward movement of the blade 3, the left surface 36 of the catch 28 rides along the outer 100 surface 29 of the shield 16 until the switch reaches its closed position, at which time the springs 32, 33, swing the catch 28 clockwise until said catch passes under the shoulder 31 of the shield 16, thereby restoring 105 the parts to the relative positions indicated in Fig. 2.

The stationary shield 16 may be mounted on the jaw-clips 2, or on the base 1, or elsewhere, as may be found convenient, or it 110 may be a part of the jaw-clips.

The proportioning of the parts, particularly the shape of the aperture 7, is illustrated somewhat conventionally, since the invention is not limited to any particular 115 shape of said aperture, nor indeed to any specific arrangement or disposition of parts not inconsistent with the present disclosure.

The hook 10 illustrated in Fig. 5 comprises preferably a wooden or other insulating pole or handle 40, upon which is fitted a ferrule 41, of bronze or other suitable material. This ferrule extends longitudinally of the handle 40 for a short distance, and then transversely of the handle, and the 125 transverse or lateral shank 14 of the ferrule terminates in a nose 9 somewhat larger than the shank but smaller than the aperture 7 of the switch with which the hook is to be used; the shank is preferably provided with 130

a guard 18 larger than the aperture 7, so that the hook cannot be inserted too far in said aperture.

From the above it will be seen that the 5 several objects of the invention are achieved, and other advantageous results attained.

As various changes might be made in the above construction, and as the above invention might be embodied in different forms, 10 it is intended that all matter set forth in the above description and in the accompanying drawings, shall be interpreted as illustrative and not in a limiting sense.

Having thus revealed my invention I 15 claim and desire to secure by Letters Patent of the United States:

1. An electric switch combining a blade member adapted to close a circuit and comprising two spaced parts substantially in 20 the plane of the blade and having registering apertures adapted to receive an operating implement, means comprising a fixed shield extending between said spaced parts, and means controlled by said shield and 25 adapted to blanket said apertures throughout a portion of the movement of said blade, to prevent removal of the implement from said apertures throughout said portion of the movement of the blade.

30 2. An electric switch combining a blade member comprising an extension having two spaced parts substantially in the plane of the blade and having registering apertures adapted to receive a hook provided with a 35 shank and a nose, fixed contact means co-operating with said blade, a fixed shield extending between said spaced parts, and means operated by said shield and blanketing said apertures throughout a portion of the 40 movement of said blade, to reduce said apertures to a size larger than said shank but smaller than said nose, to prevent removal of the hook from said apertures throughout said portion of the movement 45 of the blade.

3. An electric switch combining a blade, an extension on said blade having an aperture to receive an operating implement, and having a slot, and means comprising a fixed 50 member extending through said slot throughout a portion of the movement of the blade, and means controlled by said first means and preventing removal of said implement from said aperture throughout a 55 predetermined portion of the movement of the blade.

4. An electric switch combining a blade, an extension on said blade having an aperture to receive a hook provided with a shank 60 and a nose, and having a slot, fixed contact means co-operating with said blade, and means extending through said slot throughout a portion of the movement of the blade, and means controlled by said first means 65 and effecting the blanketing of said aper-

ture throughout a portion of the movement of the blade, to an extent sufficient to prevent removal of said hook from said aperture throughout said latter portion of the movement of the blade.

5. An electric switch combining a blade member having an aperture to receive an operating implement, fixed contact means co-operating with said blade, and a fixed shield extending between said contact means and 70 said aperture and means controlled by said shield and effecting the blanketing of the inner portion of said aperture throughout a portion of the movement of the blade, to an extent sufficient to prevent removal of 80 the implement from said aperture throughout said portion.

6. An electric switch combining a blade member having a bracket substantially in the plane of the blade and apertured to receive an operating implement and slotted in the direction of movement of said member, fixed contact means extending through said slot and co-operating with said blade when the blade is in circuit-closing position, means 85 for locking said blade in circuit-closing position, means operated by the operating implement for releasing said locking means and blanketing said aperture to an extent sufficient to prevent removal of the implement from said aperture, and means for 90 retaining said locking means in said blanketing position throughout a predetermined portion of the range of movement of the blade to prevent removal of the implement from said aperture throughout said portion.

7. An electric switch combining a blade member having a bracket substantially in the plane of the blade and apertured to receive an operating implement, a guide extending through a slot in said blade member when the blade is in circuit-closing position, means for locking said blade in circuit-closing position, and means operated by 105 said implement for releasing said locking means and simultaneously blanketing said aperture to prevent removal of said implement from said aperture, said guide maintaining said locking means in said blanketing position throughout a predetermined 110 range of the movement of the blade.

8. An electric switch combining a blade, an extension on said blade having an aperture to receive an operating implement, and having a slot, a member extending through 120 said slot throughout a portion of the movement of the blade, and means operated by said implement for blanketing said aperture to prevent removal of said implement from said aperture, said member maintaining 125 said locking means in said blanketing position throughout a predetermined range of the movement of the blade.

9. An electric switch combining a blade, an extension on said blade having an aper- 130

- ture to receive a hook provided with a shank and a nose, and having a slot, fixed contact means coöperating with said blade, a fixed member extending through said slot 5 throughout a portion of the movement of the blade, means for locking said blade in its circuit-closing position, and means operated by said hook for releasing said locking means and simultaneously blanketing said 10 aperture to reduce said aperture to a size larger than said shank but smaller than said nose, to prevent removal of said hook from said aperture, said member coöperating with said locking means to maintain said locking 15 means in said blanketing position throughout a predetermined range of the movement of the blade.
10. An electric switch combining a blade provided with a slotted bracket having an aperture to receive an operating implement, 20 fixed contact means coöperating with said blade to close a circuit, a guide registering with said slot and provided with a shoulder, a latch pivotally mounted on said blade and 25 having a catch coöperating with said shoulder to lock the blade in its circuit-closing position, means tending to maintain said latch in its locking position, and an extension on said latch partially blanketing said 30 aperture, whereby when said implement is inserted in said aperture, the initial movement of the implement in the direction for opening the switch forces said catch away from said shoulder to unlock said blade, the 35 guide preventing the removal of the implement throughout a predetermined range of the movement of the blade.
11. An electric switch comprising a switch blade, a slotted bracket secured to the blade, 40 a guide registering with the slot and having a catch lug, and a latch pivotally connected to the bracket, said bracket being at such distance from the pivot of the blade as to cause the latch to coact with the catch lug when the blade is closed, said bracket having an eye to be engaged by an operating implement, and the latch when locking and unlocking position overlapping said eye, the guide maintaining the latch in unlocking position to prevent removal of the hook 45 throughout a substantial portion of the movement of the blade.
12. An electric switch combining a blade having at its outer end, beyond the jaw clips, apertures on either side of the plane 50 of the blade for the reception of an operating implement, a pivoted latch mounted on said blade adjacent said aperture and having a portion extending into and between said apertures, a fixed shield on or adjacent 55 the jaw clips and provided with a catch coöperating with the latch to lock the blade in closed position, the initial movement of the implement in the aperture in a blade-opening direction serving to unlock the latch. 65
13. An electric switch combining a blade having at its outer end beyond the jaw clips, a pair of apertures therein for the reception of an operating implement, a locking device having a pivoted portion on the blade and a fixed catch on or adjacent the jaw clips, and means whereby the initial movement of the implement in said apertures swings the pivoted portion to unlock the blade and permit 70 it to be opened.
- In testimony whereof, I have signed my name to this specification this 4th day of November, 1916.
- 75
PHILIP H. CHASE.
